UNITED STATES PATENT OFFICE.

LOUIS C. LUGMAYR, OF WATER VALLEY, MISS., ASSIGNOR OF TWO-THIRDS
TO JULIUS A. CROWELL AND ISAAC G. CROWELL, BOTH OF SAME PLACE.

VALVE-OPERATING MECHANISM.

SPECIFICATION forming part of Letters Patent No. 252,683, dated January 24, 1882.

Application filed June 6, 1881. (No model.)

To all whom it may concern:

Be it known that I, LOUIS C. LUGMAYR, of Water Valley, in the county of Yalabusha and State of Mississippi, have invented certain useful Improvements in Valve-Operating Mechanisms for Engines, of which the following is a specification.

The object of my invention is to work the valves of steam-engines for cutting off with one eccentric, and also allow reversal of the engine with the same mechanism.

The invention consists in a slide-block connected with the eccentric and valve rod and carried by a guide pivoted to swing for shifting the valve, as hereinafter described and claimed.

In the drawings, Figure 1 is a side elevation of a vertical engine fitted with the improved valve mechanism. Fig. 2 is a sectional side view of the same with the valve mechanism in reverse position, and Fig. 3 is an illustrative diagram of the mechanism.

Similar letters of reference indicate corresponding parts.

B is the crank-shaft of the engine, provided with crank-arm d, from which a rod, k, passes to the piston-slide f.

A is an eccentric on shaft B, provided with a strap, p, from which an arm, q, extends in a plane parallel with the plane of crank-arm d.

r is a rod from the eccentric-arm q to the valve-stem v.

In suitable bearings on the bed-plate of the engine is fitted a rock-shaft, g, provided with a hand-lever, h, whereby the shaft can be given a quarter-revolution, more or less. The hand-lever moves at the side of a segment-plate, o, that is provided with pins for engaging the lever and retaining it in position as moved.

On the end of shaft g is a guide, L, carrying a slide-block, R, to which the end of the eccentric-arm q is pivoted at c. The guide L is a T-piece on the end of the shaft, fitted with slide-

rods i i, that are engaged by lugs m, projecting from block R. By means of the lever h and rock-shaft the guide L can be swung to bring the pivot c of the eccentric-arm above or below the axis on which the slide turns. The two extreme positions are shown in Figs. 1 and 2, and by the lines a a and b b in Fig. 3, thus shifting the valve. These positions give a cut-off at full-stroke, and it will be understood that by placing the slide at intermediate points the cut-off is regulated as required. In either position of the guide the revolution of shaft B moves the eccentric-arm q in and out. The slide R consequently moves back and forth on the guide L, and the valve-rod and valve are thus moved. The extent of movement of the valve is dependent upon the inclination of the guide, and the shortest movement would occur with the guide in a middle position of projecting in a straight line with the eccentric-arm.

I do not limit myself to the described means for sustaining the guide, as it may be pivoted to any suitable supports.

I am aware that it is not broadly new to operate the valves of a steam-engine with one eccentric, the same being shown in the English Patent No. 3,170 of 1875; but

What I claim, and desire to secure by Letters Patent, is—

The combination, with the shaft B, provided with the crank-arm d, connected to the piston-slide f, and the eccentric A, provided with the strap p, having arm q, connected by the rod r to the valve-stem v, of the lever h, the rock-shaft g, carrying the guide L, provided with the guide-rods i, and the slide-block R, provided with the lugs m, substantially as and for the purpose set forth.

LOUIS CHARLY LUGMAYER.
